UNITED STATES PATENT OFFICE

1,922,683

THREAD AND YARN CLEARER

Samuel Hyslop, Newton, Mass.

Application February 1, 1932. Serial No. 590,088

4 Claims. (Cl. 28—64)

This invention relates to thread and yarn clearers for use in connection with winding machines and the like for the purpose of clearing the thread or yarn of objectionable slubs, knots, 5 bunches, etc., as it is wound upon the bobbin.

This invention is an improvement upon the mechanism of like nature protected by my previously issued patents numbered respectively 1,740,242 and 1,499,929.

10 In the drawing illustrating one embodiment of my novel thread clearer:—

Fig. 1 is a plan;

Fig. 2 is a side elevation from the left of Fig. 1 showing the clearer in operative position;

15 Fig. 3 a vertical section on the line 3—3 of Fig. 1, looking in the direction of the arrow;

Fig. 4 a vertical section on the line 4—4 of Fig. 1, looking in the direction of the arrow;

20 Fig. 5 a plan, showing the clearing elements in thread-clearing positions with a thread-slot-reducing ring thereon;

Fig. 6 a detail plan of the thread clearing collar removed from the base;

25 Fig. 7 a similar view of the thread clearing ring;

Fig. 8 a side elevation of the thread-slot-reducing element shown in position in Fig. 5; and

Fig. 9 an edge elevation of the element shown in Fig. 8.

30 Referring first to Figs. 1, 2 and 3 of the drawing, my novel and improved thread clearer is shown as comprising a base 1, in this case rectangular, preferably of metal. This base has, at a suitable point thereon, (Fig. 2) a hook-like member 2, adapted to embrace the usual lifting rod 3, broken away, of a winding machine, not shown, although any convenient locking member may be used to lock it to any suitable member of the machine.

40 The inner threaded end of the member 2, Figs. 1, 2, is extended through the base 1, and provided with a nut 4 for locking the base to the member 2, and the latter to the rod 3.

The base, Fig. 1, is preferably provided with a 45 suitable number, herein two, of thread guides 5, to direct the thread to and from the clearing elements. The thread clearing elements in this improved construction, Figs. 1, 2, 6 and 7, comprise broadly a plurality, herein two, of curvilinear members, one (Fig. 7) a ring 6 with two upstanding horizontally curved posts 8, 8, slotted vertically at 9, and a neck 10 by means of which it is, to a limited extent, swingably mounted, Figs. 1, 3, 5, on a stud 11 on the base 1. The other clearing member is shown, Figs. 1, 4, 5, 6, as

a collar 12 slotted vertically at diametrically opposite points 13, and provided also with a neck 14 by means of which it is swingably mounted upon the stud 15, Figs. 1, 5, 6, dotted lines, the slots 13 in the member 12 normally registering with the slots 9 in the member 8. The member 12 is retained in its position on the stud 15 by a locking member 16 pivoted in the base and mounted to turn thereon to overhang the arm 14 of the member 12.

The member 12 overhangs the member 6 and owing to the fact that the apertures in the arms 10, 14 are slightly oblong perpendicularly of the device said members have limited relative rotary motion one within the other and about their 70 pivots 11, 15, and the slots 9 and 13 are usually made of a size to take the maximum size thread it is desired to use on a given piece of work. Downward movement of the member 6, Fig. 3, is prevented beyond the normal position by a pin 75 66 depending from the edge of member 6 in a slot 67 in the edge of the base.

To permit the ready use of a thread of different size, however, without delay, and the services of a skilled mechanic, I have conceived and 80 provided a novel thread-slot-reducing means in the form of a collar 17, Figs. 8, 9, with slots 133 like the slots 13 of the collar 12, Fig. 6, but of reduced size, which collar is slipped over and about the collar 12, Fig. 5, a cutaway portion 18 85 of the lower edge of the collar, Fig. 9, causing it to seat on the arm 14 of the collar 12 and the slots 13 in the collar 17, see Fig. 5, to register with those in the member 12 and thus to reduce 90 effectively the size of the thread that may pass therethrough.

The thread clearer is usually positioned on the machine at about the angle shown in Fig. 2, so that the members 6, 12, normally act to return 95 to normal position through gravity.

The thread 19 normally runs freely through the slots 13 in the member 12 and the slots 9 in the member 6, see Fig. 1, but, should a stub, knot or snarl or any objectionable imperfection 100 greater than the slot 13 or slot 9 approach either slot, the snarl will not pass through the slot but will be stopped thereby, and cause the member 12 to swing about its pivot 15 and the ring 6 to swing about its pivot 11, throwing the slots 13 and 105 9 out of register, and the pull of the machine will break the thread and either automatically stop the machine, by means for that purpose but not shown, or attract the attention of the operative, 110 who will give the situation the required atten-

tion, after which the members 12 and 6 will automatically swing back to normal position.

If it is desired to reduce the size of thread to be used in the machine, one need only to select 5 the collar 17 with slots of the required size, slip it over the collar 12 and the machine is instantly adapted for the desired change. The slot reducing collars are usually made with slots progressively larger by about two-thousandths of an inch 10 in width, and as many may be provided as are desired. Thus the change in the thread clearer size may be made instantly and without the services of a skilled mechanic and as frequently as desired without delay.

15 Devices for this purpose are constantly gathering lint, oil and dust and frequently need to be cleaned. Practically all wool, and much of the cotton and silk used for yarn or thread and wound upon machines on which my clearer is used, has a substantial amount of oil and other materials worked into it in the finishing of the 20 yarn to allow it to be handled conveniently in spinning and winding under unfavorable atmospheric and other conditions.

25 Lint and dust are also present in large quantities and combine with the oil to make trouble. When the slotted thread receiving members are constructed like the members 7 and 9 shown in my former Patent #1,499,929, or like the members 30 10 and 12 in my Patent #1,740,242 which, in both instances, fit closely and with no clearance, one within the other, the lint, dust and oil combine on top of and around said members and sometimes interfere with the satisfactory operation 35 of them.

To overcome this difficulty, I have designed the present improved construction. The posts 8 instead of fitting close to the collar 12 are built on a shorter radius and providing a triangular 40 dust receiving chamber 88 between them and the adjacent collar 12 which permits the oily lint and dust to fall away from the adjacent faces of the posts 8 and collar 12 and thus avoid a large part of the difficulty above referred to. 45 However, my novel clearer is very easily cleaned. The collar 12 and ring 6 and posts 8, as constructed, provide ample room within the collar 12 to use a cloth or brush, or the finger, to remove the collected lint, etc., or for the yarn to delint itself 50 while passing from one post to the other and by turning the locking member 16 to the left, Fig. 5, dotted lines, the collar 12 may be lifted from post 15 and the ring 6 and the latter lifted from the post 11 and more thoroughly cleaned if de- 55

sired. Furthermore, the shape and relation of the two thread clearing members herein so reduces the extent of the friction surfaces as compared with my earlier constructions that it is practically negligible and plenty of clearance is provided to reduce the lint and dust collecting features to a minimum.

80 My device is very simple and inexpensive to construct, easy to maintain and effective in operation.

85 My invention is not limited to the particular embodiment thereof herein illustrated and described.

I claim:

90 1. A thread clearer comprising a base, a ring and a collar thereon with registering thread slots providing normally a straight thread path, said members overlapping and eccentrically mounted for swinging movement to provide a tortuous thread path when moved by an imperfect thread, and a swinging locking member on the base to removably secure the collar and ring thereto.

95 2. A thread clearer comprising a base, means to lock it to a machine, a clearing collar and a clearing ring, the latter with upright posts within 100 in the collar, and providing therewith wedge shaped lint receiving and removing chambers, the collar and posts having radially registering thread slots, and swingable out of registering relation when either is moved by an imperfect thread.

105 3. A thread clearer comprising a base, means to lock it to a machine, a clearing collar, and a clearing ring with upright posts within the collar, the posts curved in outline and of a radius less than and circumferentially non-concentric with the collar, the collar and posts having radially 110 registering thread slots, and swingable out of registering relation when either is moved by an imperfect thread.

115 4. A thread clearer comprising a base, a clearing collar, and a clearing ring with upright posts within the collar, the posts curved in outline and of a radius less than and circumferentially non-concentric with the collar, the collar and posts having radially 120 registering thread slots, and swingable out of registering relation when either is moved by an imperfect thread, and a second thread slot changing collar with narrower thread slots therein registering with the slots in the first 125 named collar and adapted to fit snugly over the said collar to determine the size of the thread to be passed therethrough.
